CLAIM

We claim the ornamental design for a “throat for floating fountains and display aerators,” as shown and described.

DESCRIPTION

FIG. 1 is a perspective view of the throat showing the new design;

FIG. 2 is a top side elevational view thereof;

FIG. 3 is a front side elevational view thereof;

FIG. 4 is a left side elevational view thereof;

The right side elevational view is a mirror image of the left side elevational view.

FIG. 5 is a rear side elevational view thereof; and,

FIG. 6 is a bottom side elevational view thereof.

The broken line showing of unclaimed portions of the throat form no part of the claimed design.
